(57) **CLAIM**

The ornamental design for a combined necklace and pendant, as shown and described.

DESCRIPTION

FIG. 1 is a first embodiment of a front right perspective view of a combined necklace and pendant showing my new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view;

FIG. 8 is a rear left perspective view thereof; and,

FIG. 9 is a front right perspective view in open position thereof.

The necklace is shown with portions cut away to indicate a non-specified length.

1 Claim, 7 Drawing Sheets
